INVENTOR
Ernest R. Darr,
BY *Richard Oliver.*

ATTORNEY

UNITED STATES PATENT OFFICE.

ERNEST R. DARR, OF LOS ANGELES, CALIFORNIA.

SAFETY-ENVELOP.

1,278,115.

Specification of Letters Patent. Patented Sept. 10, 1918.

Application filed April 21, 1917. Serial No. 163,680.

To all whom it may concern:

Be it known that I, ERNEST R. DARR, a citizen of the United States, residing at Los Angeles, in the county of Los Angeles and State of California, have invented certain new and useful Improvements in Safety-Envelops, of which the following is a specification.

This invention relates to envelops and the principal object of the invention is to provide a device of this character which will prevent anyone from gaining access to the contents of the envelop without mutilating the same in such a manner that it will be readily detected.

Another object of the invention is to provide a series of flaps, with means for interlocking the same with the main flaps of the envelop.

Another object of the invention is to provide means for securing the interlocking flaps to the under face of the main flaps.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described and specifically pointed out in the appended claim.

In describing my invention in detail, reference will be had to the accompanying drawings, wherein like characters denote like or corresponding parts throughout the several views, and in which:

Figure 1 is a rear view of an envelop supplied with my invention.

Fig. 2 is a section on line 2-2 of Fig. 1.

Fig. 3 is a plan view of the blank before being folded.

In these figures, 1 indicates the envelop supplied with the bottom flap 2, the top flap 3 and the two end flaps 4 and 5. The top flap is provided with an extension strip 6 intermediate its ends and the bottom flap is

provided with the two extensions 7 and 8, 50 each of said extensions being located intermediate the two converging edges of the said flap. These three extensions form additional closing flaps and are provided with adhesive substances on their outer surfaces 55 at their extreme ends and the top flap is provided with two slots 9 and 10 for receiving the ends of the flaps 7 and 8 and the bottom flap 2 is provided with a slot 11 for receiving the flap 6. It will be seen that the flaps 60 6, 7 and 8 enter the slots from the top or outer surface of the main flap 3 so that they cover portions of the adhesive coated edges of the main flaps.

After the letter is inserted in the envelop, 65 the adhesive material on the outer surfaces of the three flaps and that on the under surface of the top flap is moistened and then the flaps 6, 7 and 8 are inserted in their respective slots and the top flap is pressed 70 down so that the main flap and the three locking flaps are securely held by the adhesive material and it is impossible to open the envelop without mutilating the same.

It is thought from the foregoing that the 75 advantages and novel features of my invention will be readily apparent.

I desire it to be understood that I may make slight changes in the construction and in the combination and arrangement of the 80 several parts, provided that such changes fall within the scope of the appended claim.

I claim as my invention:

A safety envelop including a pair of main flaps, the upper main flap being provided 85 with a pair of slits parallel to the longitudinal edge of the envelop and adjacent the lateral edges thereof, said flap being provided with an elongated tongue at the juncture of the two converging edges thereof, the lower 90 main flap having a pair of elongated tongues which extend parallel to and adjacent the lateral edges of the envelop to be received in the slits in the upper flap so that said tongues overlap the converging edges of the 95 upper flap, said lower flap being provided with a central slit parallel to the longitudinal edges of the envelop to receive the

tongues of the upper flap so that said tongues overlie the lower main flap, and said tongues having an adhesive substance on the outer faces of their ends so that the ends 5 of said tongues may extend through said slip and may adhere to the inner faces of the upper and lower main flaps.

In testimony whereof I affix my signature in presence of two witnesses.

ERNEST R. DARR.
